P. J. HARRAH.
WHEELED TRAY.
APPLICATION FILED FEB. 4, 1913.

1,087,878.

Patented Feb. 17, 1914.

UNITED STATES PATENT OFFICE.

PHILIP J. HARRAH, OF BLOOMFIELD, INDIANA, ASSIGNOR TO THE BLOOMFIELD MANUFACTURING COMPANY, OF BLOOMFIELD, INDIANA, A CORPORATION OF INDIANA.

WHEELED TRAY.

1,087,878.

Specification of Letters Patent. Patented Feb. 17, 1914.

Application filed February 4, 1913. Serial No. 746,230.

To all whom it may concern:

Be it known that I, PHILIP J. HARRAH, a resident of Bloomfield, in the county of Greene and State of Indiana, have invented 5 certain new and useful Improvements in Wheeled Trays; and I do hereby declare the following to be a full, clear, and exact description of the invention, such as will enable others skilled in the art to which it 10 appertains to make and use the same.

The object of my invention is to provide an improved, simple and highly efficient collapsible wheeled tray composed of but few parts and which may be readily assembled 15 for use and as easily folded for storing or packing purposes, the structure at all times presenting a neat appearance.

In the accompanying drawings, Figure 1 is a view in perspective showing my im- 20 proved tray. Fig. 2 is a view in side elevation. Fig. 3 shows the device in its folded position.

The supporting frame preferably consists of two pairs of bars 1 and 2, preferably 25 channel-bars, crossed at their centers and spaced by a cross rod 3 which also forms a pivot for such bars. On each end of this cross rod are two hinge-plates 4, 5, the inner plates 4 having each a countersunk recess 6 30 into which fits bar 1, while the outer plate 5 is likewise countersunk to accommodate bar 2. By this construction the opposed faces of the hinge plates form a bearing each for the other and prevent the creeling motion 35 that is usually present when two light bars are crossed and loosely bolted together. This construction also has the advantage that it enables the cross rod 3 to be tightly nutted to make a firm connection between the parts. 40 To limit the movements of the bars 1 and 2 I provide one of the hinge-plates with an arcural slot 7 for taking in a lug 8 of the other plate, the walls of the slot limiting the movements of the lug.

45 The supporting bars at or near their lower ends are provided with cross rods 10, while rods 12 and 13 connect these bars at their upper ends. The bars 2 at their lower extremities have stub axles 14 upon which 50 are mounted wheels 15, while to the bars 1 are pivoted the forks 16 of rear carrying wheels 17.

19 designates the tray from which, at one

end, extend short arms 20 which are pivoted to cross rod 12, preferably by having their 55 ends encircling such rod. At its other end the tray has another set of short depending arms 21, corresponding in length to arms 20, and these arms 21 are designed to detachably engage with and be supported by the 60 rod 13. The lower ends of arms 21 have open-ended slots, that is, they are of inverted U-shape to take in the rod 13.

24 is a spring clamp secured to the tray and designed to engage rod 13 to lock the 65 tray in position. Handle 25 extends from one end of the tray, and is shown in the form of a single bar secured at its ends to arms 21.

In folding the tray for packing or stor- 70 ing, after disengaging the clamp 24, tray 19 may be lifted from the rod 13, the arms 20 turning on rod 12. The supporting bars 2 are then folded over against the bars 1, turning on the rod 3. Wheels 17 may then 75 be turned to fit against wheels 15. The tray is then folded down over the supporting bars, the short arms 20 permitting it to be folded so that it will extend uniformly along one side of both sets of supporting bars. 80

Thus it will be seen that the entire tray may be quickly folded and that it will occupy but little space.

It is to be noted that all parts are folded together, it not being necessary to bodily re- 85 move any section.

I claim as my invention:

A portable tray comprising supporting bars, arranged in pairs and pivotally connected together at their centers, cross rods 90 carried each by one pair of supporting bars at the upper ends thereof, a tray having depending short arms at one end pivoted to one of said cross rods, and a second set of short arms projecting from the other end 95 of said tray and having open ended slots at their lower ends for adjustably engaging the other cross rod.

In testimony whereof, I have signed this specification in the presence of two subscrib- 100 ing witnesses.

PHILIP J. HARRAH.
